UNITED STATES PATENT OFFICE.

AUSTIN V. M. SPRAGUE, OF ROCHESTER, NEW YORK, ASSIGNOR TO TAYLOR BROTHERS, OF SAME PLACE.

RAZOR-STROP.

SPECIFICATION forming part of Letters Patent No. 276,092, dated April 17, 1883.

Application filed March 5, 1883. (No model.)

To all whom it may concern:

Be it known that I, AUSTIN V. M. SPRAGUE, of Rochester, Monroe county, New York, have invented a certain new and useful Improvement in Razor-Strops; and I do hereby declare that the following is a full, clear, and exact description of the same, reference being had to the accompanying drawings, in which—

Figure 1 is a side elevation of my improved 10 razor-strop. Fig. 2 is a perspective view of one end broken off.

My improvement relates to razor-strops in which a hone is used on one side and a leather strap on the other, the intermediate body portion being wood.

The invention consists in the combination of a concave or hollow wood body, a strap stretched from end to end over the concave, and a C-shaped spring at one end, attached to 20 the wood, resting under the leather, and serving to keep it taut by its elasticity, as herein-after described.

In the drawings, A shows a wood block, which forms the body of the instrument, having at 25 one end a handle, B. The top of the block is hollow or concave, as shown at a, and the end farthest from the handle is rounded, as shown at b.

G is a hone-surface on the plane side of the 30 block, and D is a leather strap permanently attached at both ends and resting over the concave a.

E is a metal spring, of C form, attached fast by screws or other means on the under side 35 of the block, thence extending up around the rounded end b of the block, being of greater

diameter than said rounded end, and finally turning inward horizontally, as shown. This spring forms a curved bearing over which the leather passes, and, being under strain when 40 the leather is applied over it, it constantly exerts a drawing action on the leather by its elasticity and keeps the leather always straight and taut, but with just enough of relaxation to slightly bend downward under the pressure 45 of the razor in stropping.

By the means above described screws and other devices for stretching the leather by end movement may be avoided, and much expense is saved in manufacture, and a much better 50 strop is produced, since the spring, by its stiff and broad bearing under the leather, has a tendency to draw it in a straight line and prevent any twist.

If desired, springs may be used at both ends 55 of the strop, or at either end, and, if desired, the straps may be duplicated, or two or more used on the different faces of the block.

Having described my invention, I claim—
In a razor-strop, the combination of the wood 60 body, the leather strap, and a spring attached to the body, resting under the strap, and serving to hold the strap straight by the elasticity of the spring, as herein set forth.

In witness whereof I have hereunto signed 65 my name in the presence of two subscribing witnesses.

AUSTIN V. M. SPRAGUE.
